[57] CLAIM

The ornamental design for light bulb assembly for elongated theater aisle light or the like, as shown and described.

DESCRIPTION

FIG. 1 is a top, front perspective view of a light bulb assembly for elongated theater aisle light or the like showing my new design;

FIG. 2 is a bottom, rear perspective view thereof;

FIG. 3 is a side elevational view thereof on an enlarged scale, the opposite side being a mirror image;

FIG. 4 is a rear elevational view thereof on an enlarged scale;

FIG. 5 is a front elevational view thereof on an enlarged scale.
